DESIGN FOR A TABLE

Bruno R. Weill, Statesville, N. C., assignor to Thonet Brothers, Inc., New York, N. Y.

Application August 22, 1944, Serial No. 114,970

Term of patent 14 years

(Cl. D33—14)

To all whom it may concern:

Be it known that I, Bruno R. Weill, a citizen of France, residing at Statesville, in the county of Iredell and State of North Carolina, have invented a new, original, and ornamental Design for a Table, of which the following is a specification, reference being had to the accompanying drawing, forming part thereof.

In the drawing

Figure 4 is a top perspective view of the table as it appears with two of the drawers in extended position.

I claim:

The ornamental design for a table, as shown and described.

BRUNO R. WEILL.
